(57) CLAIM

The ornamental design for a spa jet insert cover, as shown and described.

DESCRIPTION

FIG. 1 is a front right top perspective view of a spa jet insert cover according to the present invention.

FIG. 2 is a front view thereof, the rear view being a mirror image thereof.

FIG. 3 is a left side view thereof, the right side view being a mirror image thereof.

FIG. 4 is a top view thereof; and,

FIG. 5 is a bottom view thereof.

The broken lines shown represent unclaimed portions of a spa jet insert cover and form no part of the claimed design.
